UNITED STATES PATENT OFFICE.

C. C. BOMBERGER, OF WEST CARLISLE, OHIO.

IMPROVED WIND-WHEEL.

Specification forming part of Letters Patent No. 27,423, dated March 13, 1860.

To all whom it may concern:

Be it known that I, C. C. BOMBERGER, of West Carlisle, in the county of Coshocton and State of Ohio, have invented a new and Improved Wind-Wheel; and I do hereby declare that the following is a full, clear, and exact description of the same, reference being had to the accompanying drawings, making a part of this specification, in which—

Figure 1 is a vertical section of my invention, taken in the line *y y*, Fig. 2; Fig. 2, a horizontal section of the same, taken in the line *x x*, Fig. 1.

Similar letters of reference indicate corresponding parts in the two figures.

To enable those skilled in the art to fully understand and construct my invention, I will proceed to describe it.

A represents a vertical shaft, which is fitted in a suitable framing and has a series of radial frames *B* attached, in which horizontal slats *C* are placed, said slats having a tenon *a'* at the center of each end, the tenons being allowed to turn freely in the frames.

The frames *B* are of quadrilateral form, and provided with cross-bars *b*, which are between the slats and against which the edges of the slats bear when fully closed. (See Fig. 1, in which the bisected slats of one frame *B* are shown in nearly a closed state.) Any number of slats may be used in each frame, according to the dimensions of the wheel.

The slats *C* of each frame *B* are connected to a bar *D* by links *c*. The ends of the bar *D* are fitted in guides *d d* at the upper and lower ends of the frames, the bars *D* being allowed to work freely in the guides.

On the lower part of the shaft *A* and directly below the frames *B* a cam *E* is placed and allowed to slide freely up and down. This cam is formed of the segment of a circle, having an inclined plane *e* at one end. This inclined plane is directly under the path of rotation of the bars *D* of the slats, and the other portion of the cam within said path is perfectly horizontal. Underneath the cam *E* a lever *F* is placed. This lever is attached at one end to the face of the framing by a joint *f*, and the lever is connected to the un-

der side of the cam by a joint *g*, as shown clearly in Fig. 1. To the under side of the upper top piece *h* of the framing an inclined plane *i* is attached, said inclined plane being also over the path of the rotation of the bars *D* and at points in said path directly opposite the inclined plane *e*.

The outer end of the lever *F* is connected to any proper governor.

The operation is as follows: The framing is provided with a vane and so mounted that the wheel will always be kept properly facing the wind, the proper position of the framing and cam *E* relatively with the wind being shown in Fig. 2, in which the direction of the wind is indicated by black arrows. As each frame *B* passes around in the face of the wind its slats *C* are closed in consequence of its rod *D* being raised by the inclined plane *e* and the slats are kept in a closed state while before the wind by the horizontal part of the cam. As the bars *D* pass off the cam *E*, the inclined plane *i* forces the bars *D* down and opens the slats *C*, so that they will not offer any appreciable resistance in passing around in the face of the wind.

The speed of the wheel is regulated by the governor actuating the cam *E*—that is to say, raising and lowering it so as to define the length of movement of the bars *D*, the governor actuating the cams through the medium of lever *F*.

It will be readily understood that the lever *F* is to be connected in any suitable manner with the sliding sleeve of a ball-governor or other suitable governing mechanism, to which velocity or motion is given by band or other connection with the main shaft *A*. Thus any increased or diminished velocity of shaft *A* will affect the speed of the governor and cause it to operate the lever *F* accordingly.

Of course it will be seen that the higher the cam *E* is adjusted the less area the slats *C* will present to the action of the wind, and vice versa.

I do not claim, broadly, the employment or use of adjustable slats in frames attached to a shaft for the purpose of regulating the speed of the wind-wheel; but

I do claim as new and desire to secure by Letters Patent—

The arrangement and combination, with the slats C, of the vertical connecting-bars D, vertically-moving cam E, and governing-lever F, so that as the motion of the wheel increases

or diminishes the lever F will correspondingly raise or lower the cam E, and thus regulate the speed of the wheel, all as herein shown and described:

C. C. BOMBERGER.
